US0D1089252S

(12) **United States Design Patent** (10) **Patent No.:** **US D1,089,252 S**
Chen (45) **Date of Patent:** **** Aug. 19, 2025**

(54) **DISPLAY SCREEN OR PORTION THEREOF WITH A GRAPHICAL USER INTERFACE**

(71) Applicant: **AIP Technology Corporation**, Grand Cayman (KY)

(72) Inventor: **Yu-An Chen**, Zhubei (TW)

(73) Assignee: **AIP TECHNOLOGY CORPORATION**, Grand Cayman (KY)

(**) Term: **15 Years**

(21) Appl. No.: **29/918,944**

(22) Filed: **Nov. 30, 2023**

(51) **LOC (15) Cl.** **14-04**

(52) **U.S. Cl.**

USPC **D14/488**

(58) **Field of Classification Search**

USPC D14/485-495

CLAIM

The ornamental design for a display screen or portion thereof with a graphical user interface, as shown and described.

DESCRIPTION

FIG. 1 is a first image in a sequence for a display screen or portion thereof with a graphical user interface, showing our new design; and,

FIG. 2 is a second image thereof.

The outermost dashed lines illustrate the display screen or portion thereof and form no part of the claimed design. The broken line text and remaining dashed lines illustrate portions of the graphical user interface that form no part of the claimed design.

1 Claim, 2 Drawing Sheets
